UNITED STATES PATENT OFFICE.

MARK F. MADDEN, OF CHICAGO, ILLINOIS.

REST-PRODUCING STRUCTURE.

Application filed June 15, 1923. Serial No. 645,613.

The present invention is in the nature of an improvement in the rest producing structure, forming the subject of U. S. Letters Patent No. 1,415,597 granted to me May 9th, 5 1922, and the invention is predicated upon the same conditions as those set forth in the preamble of the specification of the above referred to patent.

My object, generally stated, is to provide 10 for the relieving of persons in reclining position from discomfort or pain resulting from certain portions of the body, by reason of the weight thereof, pressing against the mattress portion of the bed, where no means 15 are provided for relieving, either wholly or partially, such portions of the body from the discomforting pressure.

One of my more specific objects is to provide 20 such a structure which shall be adapted to have quickly applied thereto, in the desired predetermined positions, bodies of padding material, to suit the particular condition 25 of the patient. Another of my more specific objects is to provide a structure of the character stated which affords novel and simple means for holding the bodies of padding thereon, adapting these bodies to be readily applied to the desired positions and readily removed therefrom, as for example, 30 to permit the body of the garment to be laundered. Another more specific object is to provide a structure of the character above stated which may be readily secured, in the desired position, upon the body of a patient 35 and the bodies of padding be maintained in the proper, predetermined, positions relative to the parts of the body of the patient with which they co-operate. Another specific object is to provide a structure of the 40 character set forth which may be used either as a garment for a patient or may be spread upon the mattress portion of the bed without attachment to the person; and other objects as will be understood from the following 45 description.

Referring to the accompanying drawings:

Figure 1 is a view in elevation, of a 50 rest producing structure embodying my invention, the structure being shown in the form of a garment, but which is adapted to be laid out flatwise upon the mattress portion of a bed, the major portion of the

view showing the inside of the garment, the front portions thereof being thrown back, 55 the sleeve and body portion of the garment at the right hand side of Figure 1 being severed, to permit the entire sleeve portion and the adjacent front lap of the garment to be thrown back to fully expose 60 the inner surface of these portions of the structure, each of the sleeves having portions thereof between their ends broken away, to permit of the showing of the garment by a compact view. Figure 2 is a 65 face view of a portion of the garment at one of the pocket portions, the pocket being partly broken away to disclose the body of padding therein; and Figure 3, a section taken at the line 3 on Fig. 1, and viewed in the 70 direction of the arrow.

The structure shown is, as to its general construction, the same as an ordinary night-shirt, the opposite side portions thereof, shown as provided with the buttons and 75 buttonholes, 4 and 5, being otherwise disconnected throughout the length of the garment, whereby the garment may be unfolded to substantially flat condition as generally shown in Fig. 1. The garment may 80 be made of any suitable material, as for example, muslin, silk or other material, and is provided with padded portions which are so disposed that when the garment is applied to a patient, these pads will extend 85 against such parts of the patient that pressure, due to the weight of the patient, will be relieved either wholly or partially, as desired, against such part or parts of the patient as it is desired to be relieved of this 90 pressure. In other words, provision is made for taking the weight entirely off of a part or parts of a patient, as desired, and where desired a substantially uniform distribution 95 of pressure upon adjacent parts of the patient, is effected.

In the particular construction shown, the garment is provided at its inner side with a plurality of pockets adapted to receive bodies of padding material, such as that 100 represented at 6, these bodies of padding material, in the construction shown, comprising a casing 7 and a filling 8 of any suitable padding material, as for example, down.

The garment shown is provided with such

an arrangement of the pockets referred to that the garment is adapted to either wholly, or partially, relieve the pressure of the weight of the person against all of those portions of the person which are subjected to undesirable pressure, due to the weight of the person, when the person is reclining on a mattress. To this end, the garment is provided with four pockets, which extend generally lengthwise of the garment, at opposite sides of the center thereof, these pockets at each side being formed of two pairs 9 and 10, the pockets 9 being spaced apart from the pockets 10 as shown, thereby to provide between these pockets at opposite sides of the garment the recessed portions adapted to receive the shoulder blades of the person, the padding provided at these pocket portions thus extending at opposite sides of the shoulder blades. The garment is also provided at each side of its center line and below the pockets 10, with pockets 12 arranged in an arc-shape series, which extend slightly below the shoulder blades of the person to whom the garment is applied and partway under the arms, adjacent the arm pits, thereby relieving the weight from those ribs of the person which, if no padding were provided, would be subject to undesirable pressure. The inner side of the garment is also provided with a triangular arrangement of pockets 13 located at the center line of the garment and so arranged that the space 14 provided therebetween registers with the lower end of the spine of the person.

The garment also provides for the relieving of undesirable pressure against the knee portions of the patient, to this end the garment at each side of its center line being provided with the pairs of pockets 15, 16, 17 and 18, so disposed, as shown, that the knees of the person will extend into the spaces 19 between the pairs of pockets 16 and 17. Provision is also made for relieving the elbow portions of the patient from undesirable pressure, the garment to this end being provided at the inner surface of each sleeve, with the pockets 20, 21 and 22 affording the spaces 23 therebetween into which the elbows of the patient would extend.

All of the pockets referred to are provided for receiving padding material, for example, the pads 6, the pads being applied, of such number and of such thicknesses, as the conditions presented by the patient, require. As a structure intended merely to equalize generally, the pressure against those parts of the patient which are directly opposed to the mattress, to the end of generally distributing the pressure instead of localizing it, all of the pockets would contain padding, of the desired thickness, but if only certain portions of the

patient are to be protected against undesirable pressure, the padding material need be provided only adjacent those portions.

As hereinbefore suggested, the invention is applicable to a structure which is adapted, and intended, to be secured upon the body of the patient, or to a structure which is adapted to be laid upon the mattress for receiving the patient in reclining position, the garment shown being adapted to both of the uses above referred to, though it will be understood that my invention may be incorporated in a structure designed merely to serve as a spread for a mattress.

Where the structure is provided in the form of a garment, it is desirable that provision be made for preventing the shifting of the padded portions of the garment out of the proper positions relative to the person. As a means for accomplishing this result, the garment is shown as provided with the straps 24, 25 and 26, the straps 24 being provided for strapping the sleeve portions of the garment at its padded portions to the arms of the person, the straps 25 for the purpose of strapping the garment about the waist of the person and the straps 26 for strapping the garment, at its lower padded portions, about the legs of the person. In order that the straps 24 may be readily accessible, the sleeve portions of the garment are open along one edge, close to the innermost edges of the pockets 20.

It will be appreciated that by utilizing my invention, a person in lying down is rendered more comfortable, particularly where the person has sore spots which would be subject to such pressure normally, as to create discomfort or pain, such, as for example in the case of rheumatism and bed-sores.

According to the particular arrangement shown, the bodies of padding 6 may be readily removed from the pockets, thereby permitting the garment to be laundered, as in the case of any other washable garment, without damaging or impairing the padding material. A garment provided as described and shown, is adapted for use in conducting to the comfort of a normal person through a more even distribution of pressure against those portions of the person which oppose the mattress, and is also adapted to the relieving of sore parts of the patient and which normally would bear with undesirable pressure against the mattress, from objectionable pressure. However, many cases may arise in which it may be found desirable to position the bodies of padding otherwise than as shown, in which case the structure would be accordingly altered to suit the particular condition presented and provide the padding at the points desired.

While I have illustrated and described a particular embodiment of my invention, I do not wish to be understood as intending to

limit it thereto as the same may be variously modified and altered without departing from the spirit of my invention.

What I claim as new, and desire to secure by Letters Patent, is:

1. A body enclosing garment for the purpose set forth, provided with removable and replaceable sections of padding located in spaced relation at different points on the garment whereby to engage predetermined areas of the front and back and legs of the body of the person to whom the garment is applied, and means for holding each section of padding at its proper point and to prevent its accidental displacement.

2. A legless garment for the purpose set forth, provided with removable and replaceable sections of padding so located in spaced relation to each other as to extend above and below the knee-joint of the person to whom the garment is applied, and means for holding each section of padding at its proper point and to prevent its accidental displacement.

3. A legless garment for the purpose set forth, provided with removable sections of padding so located in spaced relation to each other as to extend above and below the knee-joint of the person to whom the garment is

applied, and means on the rear portion of the garment for engaging the leg of the person for holding the sections of padding against accidental displacement.

4. A structure adapted to serve as a garment when placed upon a patient and adapted to be spread out upon a bed to receive the patient, provided with removable and replaceable sections of padding located at different points on the structure to engage different portions of the patient to which the structure is applied as a garment or upon which the patient reclines when the structure is spread out upon a bed, and means for holding each section of padding at its proper point and prevent its accidental displacement.

5. A structure adapted to serve as a garment when placed upon a patient and adapted to be spread out upon a bed to receive the patient, provided with pockets containing removable sections of padding located at different points on the structure and engaging different portions of the patient to whom the structure is applied as a garment or upon which the patient reclines when the structure is spread out upon a bed, for the purpose set forth.

MARK F. MADDEN.
